UNITED STATES PATENT OFFICE

2,617,479

AIR DIFFUSER

Wilfred J. J. Fritz, Seattle, Wash., assignor to
 Iron Fireman Manufacturing Company, Cleve-
 land, Ohio

Application February 3, 1950, Serial No. 142,122

3 Claims. (Cl. 158—77)

1

This invention relates generally to horizontal rotary cup type oil burners and more particularly to a means for shaping the flame of such a burner by controlling the primary air injection into the combustion chamber of such a burner.

It is the principal object of this invention to provide means which can be placed in the primary air stream of an oil burner to control the pattern of primary air delivery to the combustion chamber of an oil burner and thereby control the flame pattern in the combustion chamber.

It is a second object to provide such a means which can be manually manipulated to vary its form and therefor its effect on the flame pattern.

It is a third object of this invention to provide a unit made up of a series of vanes which unit can be readily placed and held in the primary air stream of an oil burner and which vanes can be independently bent or formed to obtain the desired flame pattern in the combustion chamber of the oil burner.

It is a fourth object to provide such a unit with vanes so shaped as to be most adaptable to the purpose for which they are provided.

This application is a continuation in part of my previous application, S. N. 727,592, filed February 10, 1947, on an "Oil Burner," now Patent Number 2,591,533. In Fig. 1 of the drawings of that application, one form of the vane unit of this invention is shown in the primary air passage just back of the rotary oil atomizing cup 10 and secured to the oil transfer fitting 14.

How the above stated objects of this invention are attained is shown in the following specification and the attached drawing, in which:

Fig. 1 is an elevation in partial section of a rotary cup type oil burner.

Fig. 2 is a vertical section along the line 2—2 of Fig. 1 showing a specific form of the air diffuser of this invention.

Fig. 3 is a developed view of the diffuser of Fig. 2 as it would look if the outside band were cut and laid out flat.

Fig. 4 is a perspective drawing of one of the vanes of the diffuser of Fig. 2.

Referring now to the drawing, Fig. 1 is a simplified showing of a rotary cup type oil burner partially sectioned to show one form of the air control means of this invention. In Fig. 1 is shown an electric motor 11 driving a hollow shaft 12 through a V-belt and sheaves hidden by belt guard 13. Fuel oil from the pipe 14 traverses a small pipe inside the hollow shaft and leaves the pipe through a terminal fitting 15 inside the rotary atomizing cup 16 secured to rotating shaft 12.

2

Primary combustion air fan 17 having blades 18 is carried on and secured to shaft 12 and rotates therewith. Primary air fan housing 19 is carried on boiler front plate 20 through hinges (not shown) and in turn supports burner frame casting 21 which carries motor 11 and in which shaft 12 is journaled. Frame 21 has formed therein a primary air inlet passage 22 through which primary air is led to the eye of fan 17. Radial air directing ribs 23 are formed on the interior of fan housing 19 and carry liner 24 through screws 25. Primary air leaving fan blades 18 with a combined radial and rotary motion is directed by housing 19 to reverse its outward motion and return radially inward through the passages formed between housing 19 and liner 24 by ribs 23. Liner 24 is shaped at its inner or air discharge end to direct the air axially outward through the extended axial discharge neck of housing 19 which terminates in air cone 26.

The vane ring of this invention, made up of ring 28 having manually bendable vanes 29 secured thereto, is seen to be located within the discharge neck of housing 19 and cone 26 where it is secured by studs 30.

In the form shown, vanes 29 are each formed of sheet metal to have a support element 31 by which it is secured, as by spot welding, to the inner surface of ring 28. Radial element 32 of vane 29 is formed at a right angle to support 31 and lies in a radial plane including the axial line of the rotary cup. Adjustable vane element 33 although it is part of the complete sheet metal vane 29 is bendably adjustable with relation to radial element 32 along their line of union 34. Also element 33 is bendable parallel to line 34 at any position along its length from line 34 to its tip 35. Also element 33 is manually warpable if that is found to be desirable in service. The outer edge 36 of element 33 is curved for clearance within air cone 26. From the above description it is seen that the primary air for combustion will enter the burner through passage 22, will enter the eye of fan wheel 17, traverse blades 18, reverse its direction in housing 19, return radially through the ribbed passageway between liner 24 and housing 19, change to an axial direction in the neck of housing 19, and be given any spin desired by vane ring 28 as it leaves air cone 26 and enters the combustion chamber 37 to mix combustible with the atomized oil leaving rotary cup 16.

Depending on experience with the particular combustion chamber used, the particular rotary cup used, the particular air cone used, and the

amount and type of oil being burned, the elements 33 of vanes 29 can be bent in the field to dress the flame to give the best results for the particular installation. It should be noted that in certain circumstances it is possible and will be desirable to vary the angularity of certain of the elements 33 with respect to their elements 32 differently from the angularity of other of the elements 33 with respect to their elements 32.

Having thus shown and described a specific construction and use of the primary air controlling vane system of this invention in connection with a rotary cup type of oil burner and noting that another specific construction is shown but not claimed in my previous application, S. N. 727,592, I claim:

1. A rotary cup atomizing type oil burner including means to conduct primary air to the combustion zone of said burner, means for forcing a stream of primary air through said conducting means and means for whirling said air in said conducting means, said conducting means comprising a cylindrical conduit terminating in an inwardly converging conical extension thereof, said whirling means comprising a vane ring and a plurality of vanes, said vane ring comprising a cylindrical body fitted to the interior of the cylindrical portion of said conducting means adjacent the conical extension thereof, each of said vanes comprising a radial section and a wing section positionably secured to said radial section along a radial edge thereof, said radial section being radially secured to said vane ring along the outer edge of said radial section, said radial section being positioned with said outer edge parallel to the axis of said conduit, and said wing section extending positionably into said conical end extension of said conduit at an angle to said radial section.

2. A cylindrical air conduit having an end extension in the form of a right angled frustrated cone and means for forcing air to flow through said conduit and out through said conical extension thereof, together with means for whirling said air in said conical extension of said con-

duit, said whirling means comprising a vane having a radial section and a wing section, said radial section of said vane being fixed interiorly of said cylindrical conduit in a plane including the axis thereof, said wing section of said vane being positionably secured to said radial section along an edge thereof radial of said conduit, and said wing section of said vane extending into the conical extension of said conduit at an angle to said radial section.

3. A cylindrical air conduit having an end extension in the form of frustrated cone and means for causing air to flow through said conduit and out through the conical end extension thereof, together with means for whirling said air passing out through said extension, said whirling means comprising a plurality of vanes equally spaced angularly about the axis of said conduit, each of said vanes having an upstream end section and a downstream end section, the upstream end section of one of said vanes being secured within the interior of said cylindrical section of said conduit in a plane including the axis of said conduit, the downstream end section of said one of said vanes being positionably secured to said upstream section along an edge thereof radial to said conduit, and the downstream end section of said one of said vanes extending within said conical extension of said conduit at an angle to the upstream end section of said vane.

WILFRED J. J. FRITZ.
